UNITED STATES PATENT OFFICE.

EDWARD M. CLARK, OF DAVENPORT, IOWA.

DESIGN FOR AN ADVERTISING SIGN.

Application filed November 17, 1928. Serial No. 28,926. Term of patent 14 years.

To all whom it may concern:

Be it known that I, EDWARD M. CLARK, a citizen of the United States, residing at Davenport, in the county of Scott and State of Iowa, have invented a new, original, and ornamental Design for Advertising Sign, of which the following is a specification, reference being made to the drawing forming a part thereof.

In the drawing, Fig. 1 shows an elevation of my new advertising sign; Fig. 2 shows an

edge view thereof from the right side of Fig. 1.

This sign has a colored ornamental band around the margin thereof as shown in Fig. 1 and has colored ornamental designs at the top and bottom and in the corners thereof.

I claim—

The ornamental design for an advertising sign as shown and described.

EDWARD M. CLARK.
